BRACKET TO SUPPORT RADIATORS.

1,088,861.

Specification of Letters Patent.

Patented Mar. 3, 1914.

Application filed April 9, 1913. Serial No. 759,885.

To all whom it may concern:

Be it known that we, WILTSIE F. WOLFE, citizen of the United States, and resident of Atlantic City, Atlantic county, State of New Jersey, and CHARLES R. FOWLER, NELSON C. SCHROEDER, and ALFRED S. MAPPETT, citizens of the United States, and residents of the city and county of Philadelphia, State of Pennsylvania, have invented an Improvement in Brackets to Support Radiators, of which the following is a specification.

Much difficulty has been experienced in supporting radiators upon the walls of a building and upon like surfaces owing to the expansion and contraction of the radiators due to the changes in temperature, and also owing to the settling of the walls, floors and foundations. This is particularly the case with radiators made up of tubular radiator-units coupled together. When such radiators are rigidly secured to the wall or other surface the expansion and contraction strains have a tendency to weaken the couplings or connections and produce leaks. Similar strains result when there is a settling of the walls, floors or foundations after the radiators have been erected.

It is the object of our invention to overcome these difficulties by means of a bracket for supporting the radiator—whether it be a unit or plurality of connected units—with provision for free expansion and contraction both vertically and horizontally. This result we accomplish by suspending the radiator on a bracket-piece or support having provision for lateral movement.

Our invention also includes means for adjusting the bracket-piece to suit the desired position of the radiator and to bring all units into proper relation with one another.

It also includes means for holding the radiator or unit on its bracket-piece without impeding the freedom of movement under expansion and contraction.

While our invention is not restricted to radiators of any particular type, it is intended primarily for use in connection with tubular wall-radiators and has been shown in connection with a Fowler and Wolfe radiator.

In the drawings:—Figure 1 is a front

elevation of a radiator unit supported by a pair of our brackets; Fig. 2 is a side elevation of the bracket secured to the wall with the radiator unit in vertical section on the line A—A of Fig. 1 on an enlarged scale; Fig. 3 is a front elevation of the bracket; and Fig. 4 is a vertical section on the line B—B of Fig. 3.

a is an elongated plate provided at the top and bottom with holes *a'*, *a''* respectively, by which the plate may be fastened to the wall by screws *g*. The plate is preferably provided with bosses or ribs *a³* at the back adjacent to the holes *a'*, *a''*, so that the back of the body will be offset from the wall when the plate is attached, as shown in Fig. 2.

b is a ledge extending forward from the top of the plate which acts as a support for the rod *c* which carries the bracket-piece *d*. This bracket-piece is in the form of a hook extending from a block *d'* threaded on the end of the rod *c*. The upper end of the rod is provided with a head *c'* resting on the ledge *b*, and the opening *e* in the ledge *b* through which the rod extends is sufficiently large to allow a slight lateral play, so that the rod and bracket-piece *d* may move laterally.

The radiator-unit *f* is supported by the bracket-piece *d* which projects under one of the tubes, as the central cross-tube *f'*, and one or more brackets may be used with a single radiator-unit. In Fig. 1 we have shown the unit supported by two brackets. As the rod *c* fits loosely in the opening *e* it may rock laterally to an extent proportional to the amount of play, permitting the radiator-unit to move correspondingly. Consequently with a radiator composed of a plurality of units coupled together in the usual manner the radiator may expand and contract laterally under variations of temperature without any strain on the couplings or connections by swinging the brackets; and, as the units merely rest on the bracket pieces *d*, vertical expansion and contraction are unimpeded.

It is desirable that means should be employed to hold the radiator-unit securely upon its bracket. For this purpose we prefer to employ headed hooks *h*, which are inserted between the vertical tubes *f''* of the

unit with the hooked ends h' engaging the rod c and the heads h^2 , which are adjustable, bearing upon the outer surfaces of the tubes. These hooks, while holding the units securely upon their brackets, do not interfere in any way with the freedom of movement of the unit under expansion and contraction. They will move laterally with the radiator unit and its support and are not tight enough to impede vertical movement.

As the bracket-pieces d are supported by the threaded blocks d' on the threaded ends of the rods c , they may be adjusted vertically by turning the rod, the head c' of which is adapted for this purpose. Thus each bracket may be raised or lowered with reference to the plate a , which is rigidly secured to the wall, to bring the unit which it supports into proper position with reference to other units and to compensate for any settling in the floor or foundation.

What we claim is as follows:

1. A bracket for supporting a radiator section against a wall and in a position parallel thereto, consisting of a piece rigidly secured to the wall or other surface, and a swinging bracket-piece having a swinging connection with the wall piece and provided with means for supporting the radiator section, whereby the radiator section may move laterally across and parallel to the surface of the wall with the movement of the bracket piece under expansion and contraction.

2. A bracket for supporting a radiator consisting of a plate adapted to be fixed to a wall or other surface; a rod suspended at its upper end by said plate with provision for lateral movement over the surface of said plate and the wall by which it is supported, said rod being provided with a support upon which a sectional radiator may be supported or may rest and be secured in a position parallel to the surface of the wall with capacity for lateral movement with the bracket-piece.

3. A bracket for supporting a radiator consisting of a plate adapted to be affixed to the wall or other surface, a rod suspended at its upper end by said plate with provision for lateral movement, and a bracket-piece carried by said rod with provision for vertical adjustment thereon, upon which the radiator is adapted to rest.

4. A bracket for supporting a radiator consisting of a plate adapted to be affixed to the wall or other surface, a rod suspended at its upper end from said plate with provision for lateral movement and threaded at

its lower end, a threaded block carried by the threaded portion of said rod and adjustable thereon by the rotation of the rod, and a bracket-piece upon which the radiator is adapted to rest carried by said adjustable block.

5. A bracket for supporting a radiator section against a wall and in a position parallel thereto, consisting of a piece rigidly secured to the wall or other surface, and a swinging bracket-piece having a swinging connection with the wall piece at the upper end and provided at the bottom with means for supporting the radiator section, whereby the radiator section may move laterally across and parallel to the surface of the wall with the movement of the bracket-piece under expansion and contraction.

6. A bracket for supporting a radiator section against a wall and in a position parallel thereto, consisting of a piece rigidly secured to the wall or other surface, and a swinging bracket-piece having a swinging connection with the wall piece at the upper end and provided at the bottom with means for supporting the radiator section, whereby the radiator section may move laterally across and parallel to the surface of the wall with the movement of the bracket-piece under expansion and contraction, and means carried by the bracket-piece to secure the section thereto.

7. A bracket for supporting a radiator section against a wall and in a position parallel thereto, consisting of a piece rigidly secured to the wall or other surface, and a swinging bracket-piece having a swinging connection with the wall piece at the upper end and provided at the bottom with means for supporting the radiator section, whereby the radiator section may move laterally across and parallel to the surface of the wall with the movement of the bracket-piece under expansion and contraction, and means carried by the bracket-piece to secure the section thereto, consisting of a hook having its outer end bearing on the radiator section and connecting at the inner end with the swinging bracket.

In testimony of which invention, we hereunto set our hands.
